(57) **CLAIM**

The ornamental design for a boat motor fairing, as shown and described.

DESCRIPTION

FIG. 1 is a first perspective view of a first embodiment of a boat motor fairing;

FIG. 2 is a second perspective view of the boat motor fairing of FIG. 1;

FIG. 3 is a front view of the boat motor fairing of FIG. 1; FIG. 4 is a back view of the boat motor fairing of FIG. 1; FIG. 5 is a left side view of the boat motor fairing of FIG. 1;

FIG. 6 is a right side view of the boat motor fairing of FIG. 1;

FIG. 7 is a top view of the boat motor fairing of FIG. 1; and, FIG. 8 is a bottom view of the boat motor fairing of FIG. 1. The broken lines shown in the drawings depict environmental structure and do not form part of the claimed design.
